UNITED STATES PATENT OFFICE.

LOUIE STERN, OF NEW YORK, N. Y., ASSIGNOR TO STERN & WEISBART, OF NEW YORK, N. Y., A PARTNERSHIP COMPOSED OF SAID LOUIE STERN AND BENJAMIN WEISBART.

LOCK.

1,426,122.

Specification of Letters Patent Patented Aug. 15, 1922.

Application filed April 30, 1921. Serial No. 465,912.

To all whom it may concern:

Be it known that I, LOUIE STERN, a citizen of the United States, and a resident of New York, borough of Manhattan, in the county of New York and State of New York, have invented certain new and useful Improvements in Locks, of which the following is a specification.

This invention relates to locks, and particularly to that class thereof which employs a pair of opposed bolts, movable in opposite directions, for engaging a keeper. The object of my improvements is to provide a lock of the class specified, of simple construction and having means for coaction with the keeper for causing the bolts to engage the keeper automatically.

With these ends in view, my improvements comprise features illustrated in their preferred embodiment in the accompanying drawings, wherein:

Figure 1 is a sectional view taken substantially on line 1—1 of Fig. 2, showing the lock in engagement with the keeper. Fig. 2 is a sectional view, taken substantially on line 2—2 of Fig. 1, showing the several parts in the same relative positions as in Fig. 1. Fig. 3 is a sectional view similar to that of Fig. 2, but showing the parts in different positions than in the earlier views. The scale of all three views is the same.

The present invention is in the nature of improvements on the invention set forth in Letters Patent of the United States No. 1,215,888, granted to me February 13, 1917, and to which reference may be had. That earlier patent included a latch, and the present case includes a similar member; but the latch of the present case, while operating in a somewhat similar way to the latch of that earlier patent, has a distinctly different function and in its operation accomplishes a distinctly different result.

Directing attention now to the drawings, lock case 3 is adapted to be secured by screws 4 to the inner face of a door 5, or other member which it is desired to fasten by means of said lock, to an adjoining abutment or jamb as 6, and to which latter is secured keeper 7 by screws 8. Within said casing is bolt 9, or a pair of bolts 9, 10, carried by shanks 11, 12, respectively. Preferably, and as illustrated, said bolts are in axial alignment, and said shanks are mount-

ed and guided for movement in parallelism with the common axis of said bolts. Said shanks are urged inwardly toward each other by push springs 13, 14, respectively. Said shanks are preferably of L shape, their tails 15, 16, respectively, being turned inwardly toward each other and overlapping; shank 11 being materially longer than shank 12, whereby said tails not only overlap without interference, but space is provided therebetween for upstanding portion 17 of case 3, the parallel edges of which serve as guides for one side of each of said tails. Said portion 17 also serves as pivot block for lever 18 and its rotatable actuator 19. Said lever 18 is double ended, and each end carries a pin for engagement with a slot in the tails, respectively, of said shanks, as pin 20 in slot 21 of tail 15, and pin 22 in slot 23 of tail 16. For holding tail 15 in the position of Fig. 2, or in the position of Fig. 3, sliding catch 24 is provided.

About midway of case 3, in Figs. 2 and 3, is latch 25, mounted for reciprocation in a direction normal to that of the direction of movement of bolts 9, 10. Said latch, when bolts 9, 10 are retracted, Fig. 3, protrudes into the space between the inwardly facing ends of said bolts, and which space is largely occupied by keeper 7, when the case and keeper are brought into engaging position, as in Figs. 1 and 2. When so brought into engaging position, the beveled end 25^a of latch 25 encounters said keeper and is forced back thereby from the position of Fig. 3 to that of Figs. 1 and 2. Said latch is guided for movement in seat 26 in case 3, and is also provided with stem 27, guided in seat 28 in wall 29 upstanding in case 3. Spring 30 tends to urge said latch outwardly. Said latch is provided with foot 31 for engagement with post 32 of shank 12, when that shank is in its retracted position, Fig. 3. Keeper 7 is preferably provided with a passage 7^a therethrough, and which passage is entered at either end by bolts 9, 10, respectively, when the lock is operated to engage said keeper.

The operation of my improved lock is as follows: The parts being in the relative positions of Fig. 3, with latch 25 projecting from case 3 and foot 31 of said latch in engagement with post 32 of shank 12, whereby bolts 9, 10 are maintained in their retracted

positions, respectively, door 5 is moved downwardly, Fig. 1, thereby causing beveled end 25^a of latch 25 to encounter keeper 7 and be forced backwardly thereby against the pressure of spring 30. As that latch is forced backwardly to the left, foot 31 thereof rides off post 32, thereby permitting springs 13, 14 to act against shanks 11, 12, respectively, and whereby those shanks and their respective bolts 9, 10 are forced toward each other into engagement with keeper 7, as shown in Fig. 2. The movement of shanks 11, 12 from the positions of Fig. 3 to those of Fig. 2 will swing lever 18 from the position of Fig. 3 to that of Fig. 2. For unlocking, actuator 19, or the key actuated barrel, may be turned to move lever 18 and shanks 11, 12 from the positions of Fig. 2 to those of Fig. 3, thereby withdrawing bolts 9, 10 from engagement with keeper 7. Then if the door be opened, latch 25 will be forced outwardly by spring 30, thereby causing foot 31 to pass onto post 32 of shank 12, whereby said bolts will be held in their retracted positions, respectively, ready for a repetition of the described operation.

I claim:

1. A lock including in combination a pair of opposed bolts, spring means for urging said bolts toward each other, a latch adapted for movement transversely to the direction of movement of said bolts, spring means for urging said latch in one direction, means on said latch for engagement with one of said bolts for holding said bolt in retracted position, and means connecting said bolts and adapted for causing said bolts to move in unison in opposite directions.
2. A lock including in combination a pair of opposed bolts, spring means for urging said bolts toward each other, a latch adapted for movement transversely to the direction of movement of said bolts, spring means for urging said latch in one direction, means on said latch for engagement with one of said bolts for holding said bolt in retracted position, means connecting said bolts and adapted for causing said bolts to move in unison in opposite directions, and

means for locking said bolts in either their retracted or extended positions, respectively.

3. A lock including in combination a pair of opposed bolts each carried by a shank, means for guiding said shanks for parallel movement, spring means for urging said shanks toward each other, hand actuated means for moving said shanks away from each other, a latch mounted for movement transversely to the direction of movement of said shanks, spring means for urging said latch in one direction, means on said latch for holding one of said shanks in retracted position, a keeper for receiving said bolts, and means on said latch for engagement with said keeper for moving said latch for releasing the shank held in retracted position by said latch.

4. A lock including in combination a pair of opposed bolts, spring means for urging said bolts relatively toward each other, a latch normally between said bolts adapted for movement transversely to the direction of movement of said bolts, spring means for urging said latch in one direction, means on said latch for engagement with one of said bolts for holding said bolt in retracted position and means connecting said bolts adapted for causing said bolts to move in unison in opposite directions.

5. A lock including in combination a pair of opposed bolts each carried by a shank, means for guiding said shanks for parallel movement, spring means for urging said shanks relatively toward each other, hand actuated means for moving said shanks against their spring urging means, a latch between said shanks mounted for movement transversely to the direction of movement of said shanks, spring means for urging said latch in one direction, means on said latch for holding one of said shanks in retracted position, a keeper for receiving said bolts, and means on said latch for engagement with said keeper for moving said latch for releasing the shank held in retracted position by said latch.

In witness whereof, I hereby affix my signature this 29th day of April, 1921.

LOUIE STERN.
